[57] CLAIM

The ornamental design for a dispensing cap for a container, as shown and described.

DESCRIPTION

FIG. 1 is a top plan view of a dispensing cap for a container showing my new design;

FIG. 2 is a bottom plan view thereof;

FIG. 3 is an elevational view, the opposite side being the same in appearance;

FIG. 4 is a top perspective view; and

FIG. 5 is a medial sectional view thereof.

FIG. 1

FIG. 2

FIG. 3
